WIRE FEED MACHINE

Frank A. Newcombe, Nutley, N. J., assignor to
Westinghouse Electric Corporation, East Pitts-
burgh, Pa., a corporation of Pennsylvania

Application June 20, 1946, Serial No. 678,080

5 Claims. (Cl. 242—45)

1

This invention relates to means for feeding wire to a cutting machine or other apparatus using the same.

The principal object of my invention, generally considered, is to provide an improved wire feed control, particularly adapted for feeding tungsten wire and the like to coil-cutting machines or other apparatus using such wire.

Another object of my invention is to provide a wire feed which is motor driven to turn a spool of wire to keep unwound a relatively long length of wire and hold the same under predetermined tension, readily available to a coil-cutting or other machine using such wire, automatic controls being provided to stop the motor when the desired length has been unwound and start it again when necessary to replenish the unwound supply.

Other objects and advantages will become apparent as the description proceeds.

Referring to the drawing:

Fig. 1 is a diagrammatic elevational view of apparatus embodying my invention.

Fig. 2 is a fragmentary sectional view on the line II—II of Fig. 1, in the direction of the arrows.

Machines, such as those which form and cut coils of tungsten wire used for making lamps, need a supply of such wire always available in unwound condition and under a predetermined relatively-small tension, so that as the wire is drawn from a spool and cut, the jerky pull on such wire will not cause breakage, nor will any kinked wire portions be delivered to the using machine.

The wire-feeding device previously employed has not been entirely satisfactory because an extensive amount of maintenance was required to keep it in operating condition. I have therefore developed a simplified control for feeding wire to machines, and particularly those for forming and cutting coils for use in electric lamps. However, my feed control is adapted for supplying wire to any machine which uses it and is not limited to feeding wire of tungsten or the like.

Referring to drawing, like parts being designated by like reference characters, there is shown a spool 11 from which wire 12 is being drawn and fed to a machine 13 using it, as over pulley 20. Although the machine 13 is designated as a coil-cutting machine and indicated only diagrammatically, it will be understood that it represents any machine that makes use of such wire.

It is not satisfactory for the wire 12 to feed

directly from the spool 11 to the using machine because of the non-uniform rate at which the wire is needed. It is, therefore, necessary to have some unwound length of wire under predetermined light tension, so that jerky pulling on the wire by the using machine 13 will not break or kink it. For this reason, I feed the wire 12 supportingly under a pulley 14, freely rotatable on a light weight carriage 15 which slides on guide rods 16 and 17. These rods may be relatively long, so that when the reel 15 is in its normally lowermost position, a relatively great length of wire under predetermined light tension, is available for immediate use by the machine 13.

15 The spool 11 is tight on a shaft 18 driven by a suitable small motor 19 with or without reduction gearing 21. The speed of the motor, which may be varied by adjustment of the rheostat 30, is such that, when operating, the wire 12 is un-

20 wound faster than it is used by the machine 13, so that the carriage 15 moves from the full line position to that shown in dotted lines in Fig. 1. The drag of the gearing 21 and/or motor 19

25 should be enough to prevent the tension of the wire 12 from turning the shaft 18. In order to control the operation of the motor, the reel 15 carries a cam 22 which alternately actuates the normally-open start switch 23, as by engaging the roller 24 on operating member or lever 25,

30 and the normally-closed stop switch 26 disposed below said start switch, as by engaging the roller 27 on its operating member or lever 28.

The start switch 23 is connected to the solenoid 29 of the line starter 31 of the motor 19, so that

35 upon closure of the switch 23 upon upward movement of the weight reel to about the position shown in full lines in Fig. 1, the solenoid is energized from supply source 32 through switch 33, line 34, start switch 23, line 35, and back to the

40 source through lines 36, 37, and 38, stop switch 26, and line 39. This energization of the solenoid 29 draws the armature 41 to the left, as viewed in Fig. 1, closing connected switches 42, 43 and 44 against the action of biasing spring 45.

45 Switch 42 on closing keeps the solenoid 29 energized after the circuit through the switch 23 is broken, as the weight reel 15 moves downward and its cam 22 releases the roller 24. The closing of the switches 43 and 44 completes the circuit to and energizes the motor 19 through lines 34, 46, switch 44, lines 47 and 48, and back to the source of power through lines 49, 51, speed-control rheostat 30, switch 43, lines 37 and 38, stop switch 26, and line 39.

50 55 Inasmuch as the motor when running feeds the

wire 12 from the spool 11 faster than it is used by the machine 13, the weight carriage 15 then descends to the dotted position where its cam 22 engages the roller 21 on the switch operating member 28, causing the switch 26 to open, thereby breaking the circuit to and stopping the motor 19. This also deenergizes the solenoid 29, allowing the switches 42, 43 and 44 to open under the influence of the spring 45, so that the motor 19 does not again run until enough wire is drawn by the machine 13 to raise the carriage 15 into engagement with the roller 24 of the switch 23, as indicated in full lines, whereupon the motor is started and the unwinding operation is repeated.

In order to prevent continued operation of the machine 13 if something goes wrong, like the breaking of the wire 12, a normally closed cut-out switch 52 is provided which is opened after the weight carriage 15 drops below the normal lowermost position, indicated in dotted lines, so that it engages the operating arm 53 on said switch and breaks the circuit through lines 54 and 55 to the line starter 56 of the motor (not shown) which operates the machine 13.

The normal operation of the aforescribed mechanism is as follows:

Assuming it to start with the motor 19 deenergized and the weight carriage 15 in lower position, operation of the machine 13 draws on the wire 12 over pulley 20, raising the carriage 15 until it engages the roller 24 and closes the switch 23. This starts the motor 19 which unwinds the wire 12 from the spool 11 at a constant speed faster than used by the machine 13, so that the carriage 15 moves downward, finally engaging the roller 21, opening the switch 26, and deenergizing the motor 19. This causes the carriage 15 to be raised by continued operation of the machine 13 and the operation is repeated.

From the foregoing disclosure, it will be seen that I have provided a wire-feed control which always maintains a desired length of wire under light tension, ready for being immediately drawn to a coil-cutting or other using machine, thereby normally preventing breaking or kinking of the wire, as well as having a satisfactory supply available at all times. Although certain forms of the control switches have been illustrated, it will be understood that these, as well as other parts of the mechanism may be modified within the spirit and scope of the invention, as defined by the appended claims.

I claim:

1. Apparatus for feeding wire comprising a supply spool, a motor connected in driving relationship with said spool, a weight carriage, a pulley rotatable thereon and under which the wire from said spool supportingly passes on its way to a using mechanism, whereby said wire is held under a predetermined amount of tension, a normally-open start switch closed by said weight carriage when in an upper position to energize said motor and start unwinding the wire from said spool until the weight carriage carried thereby descends to a lower position, a normally-closed stop switch opened by said weight carriage when in lower position in order to then deenergize said motor, a line starter for said using mechanism, and a normally-closed cut-out switch in the circuit to said line starter and disposed directly below said weight carriage, so that it is opened in case the weight carriage descends below its normally lowermost position, as upon breakage of the wire.

2. Apparatus for feeding wire comprising a supply spool thereof, means for unwinding wire from said spool, a weight carriage, a pulley rotatable thereon and under which the wire from said spool supportingly passes on its way to a using mechanism, whereby said wire is held under a predetermined tension, a normally-open start switch closed by said weight carriage when in upper position to energize said unwinding means and cause the wire to pass from said spool until the weight carriage descends a predetermined distance, a normally-closed stop switch opened by said weight carriage at the end of said predetermined distance, in order to then deenergize said unwinding means, means for driving said using mechanism, and a switch in the circuit with the power supply to said driving means and disposed directly beneath said carriage, so that it is opened in case said carriage descends below its normally lowermost position, as upon breakage of the wire.

3. Apparatus for feeding wire comprising a supply spool, a motor connected in direct driving relationship with said spool, a weight carriage, relatively long rods on which said carriage is guidingly mounted for up and down movement, a pulley rotatably mounted on said carriage and under which the wire from said spool supportingly passes on its way to a using mechanism, a normally-open start switch, an operating lever for said switch pivoted adjacent one end, a roller pivoted on said lever adjacent its other end, a cam on said carriage to engage said roller and close said start switch when the carriage is in an upper position, to energize said motor and start unwinding the wire from said spool until the carriage descends to a lower position, a normally-closed stop switch, an operating lever for said switch pivoted adjacent one end, a roller pivoted on said lever adjacent its other end, the cam on said carriage when in a lower position engaging said roller and opening said stop switch, deenergizing said motor and allowing the using mechanism to raise the weight carriage by drawing on the wire, until it again closes the start switch for a repetition of the operation.

4. Apparatus for feeding wire comprising a shaft-carried supply spool, a motor with a line starter including an actuating solenoid and connected in direct driving relationship with said shaft, a cam-carrying weight carriage, a pulley rotatably mounted on said carriage and under which wire from said supply spool supportingly passes on its way to a using mechanism, relatively long rods on which said carriage is guidingly mounted for up and down movement, a normally-open start switch, an operating lever for said switch pivoted adjacent one end, a roller pivoted on said lever adjacent its other end, said carriage cam being engageable with said roller to close said start switch when said carriage is in an upper position, to energize said line starter solenoid, start the motor and keep it unwinding wire from said supply spool, even if the weight carriage drops and allows the start switch to reopen, until said weight carriage descends to a predetermined lower position, a normally-closed stop switch, an operating lever for said switch pivoted adjacent one end, a roller pivoted on said lever adjacent its other end, the cam of said carriage when in a lower position engaging said roller and opening said stop switch, in order to deenergize said motor and allow the using mechanism to raise the weight carriage by drawing on the wire, until its cam again closes the start switch for a repetition of the operation.

5. Apparatus for feeding wire comprising a supply spool tight on a shaft, a motor geared to said shaft, a weight carriage, rods on which said carriage is guided for up and down movement, a pulley rotatable on said carriage and under which the wire from said spool supportingly passes on its way to a using mechanism, a normally-open start switch, an operating lever for said switch pivoted adjacent one end, a roller pivoted on said lever adjacent its other end, a cam on said carriage to engage said roller and close said start switch when the carriage is in an upper position, a normally-closed stop switch disposed below said start switch, an operating lever for said switch pivoted adjacent one end, a roller pivoted on said lever adjacent its other end, the cam when said carriage is in a lower position engaging said roller and opening said stop switch, said closing of the start switch and opening of the stop switch being effected by said motor alternately unwinding
